UNITED STATES PATENT OFFICE

2,266,911

CENTRIFUGAL EXTRACTOR

Henry G. Schwarz, Denver, Colo., assignor to The Schwarz Engineering Company, Inc., San Francisco, Calif., a corporation of Nevada

Original application May 25, 1935, Serial No. 23,411. Divided and this application May 16, 1936, Serial No. 81,487. Renewed June 21, 1937

4 Claims. (Cl. 210—68)

This invention relates to a centrifugal juice extractor, and while more particularly designed for extracting fruit juice, it is, of course, not limited to this particular use, but will be found valuable wherever it is desired to break up, shred, and extract and juice from any liquid laden solid material.

The principal object of the invention is to provide an extractor which will be continuous and automatic in its operation; which will have an exceedingly large capacity with a minimum of size and minimum power consumption; which can be minutely and easily adjusted to obtain a maximum extraction from any given product; and which will be economical to manufacture and service.

The invention relates more particularly to the type of extractor shown in applicant's copending application, Serial No. 23,411, filed May 25, 1935, which has issued as Patent No. 2,054,342, of which this application is a division.

Another object is to provide a machine of this type which progressively tear open and break down the structure and cells of the solid material and expel the liquids such as moisture, juices, oils, fats, etc., as the material progresses on its way from the inlet to the discharge.

Still another object of the invention is to so construct the device that a classification or separation of the extracted juices may be had if desired.

A further object is to eliminate all frictional contacts, reciprocating motions, etc., and to provide a machine having only one moving unit so that a long life and freedom from repairs is assured.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a vertical section through the improved extractor.

Fig. 2 is a fragmentary detail section through the screen ring.

Fig. 3 is a horizontal section, taken on the line 3—3, Fig. 1.

Fig. 4 is a similar section, taken on the line 4—4, Fig. 1.

Fig. 5 is a similar section taken on the line 5—5, Fig. 1.

Fig. 6 is a detail section through the screen bell, taken on the line 6—6, Fig. 1.

5 The principle embodied in this machine could be carried out with various mechanical constructions. The drawings illustrate one embodiment which has proven very satisfactory.

The machine illustrated comprises a base casting 10 upon which rests a cylindrical housing 11. An extracting cylinder 12 is supported on the housing 10 which in turn supports a head casting 13. A vertical shaft 14 extends between a bearing 15 in the head casting 13 and a second bearing 16 in the base 10. The weight of the shaft is supported on a thrust bearing 17 which can be vertically adjusted by means of a pressure screw 18.

The base 10 is formed with a peripheral juice channel 19 from which one or more juice discharge pipes 20 lead. The mid portion of the base is open for the discharge of pulp therethrough. The pulp discharge and the juice channel is divided by an inwardly inclined inner wall 21. The housing 11 is formed with an inclined or conical inner wall 21 leading downwardly and outwardly to the juice channel 19. The head casting 13 is provided with a feed chute or hopper 22 through which the material is fed to the machine.

20 The shaft 14 carries one or more "star wheels" or series of radial, inclined, shredding blades 23. In the drawings, two "star wheels" are illustrated, one positioned above the other. A cylindrical shredding ring 24 provided with shredding teeth 25 is set into the cylinder 12 around the upper star wheel. The tooth 25 may have any form suitable to the product being shredded. They may comprise vertical gear-like teeth or relatively sharp shredding points as desired.

25 A cylindrical extracting screen 26 surrounds the second star wheel. This screen is carried in a removable screen ring 27 set into the cylinder 12. The screen ring 27 is illustrated in detail in Fig. 2, and is formed with a series of vertical ribs 28 on its inner surface which support the screen and form vertical juice channels behind the screen which open through discharge openings 29 at the bottom. Below the openings 29 in the ring 27 terminates a conical series of teeth 30.

30 A spreader cap 31 surrounds the shaft 14 below the star wheels 23 and covers a bladed shredding cone 32 which is keyed to the shaft 14.

35 The top of the cap 31 is formed with a series

of inclined blades 39 of various heights. The cone 32 is formed with outwardly extending blades 33, about which a conical extracting screen 34 is secured. A conical bell 35 surrounds the screen 34. The bell is secured to the ribs 33 of the cone 32 by means of suitable cap screws 48 (see Fig. 6) so as to rotate therewith and is provided with a series of inwardly extending ribs 36 which divide the space between the screen and the inner wall of the bell into a series of vertical fluid channels which discharge at the bottom through passages 37.

The shaft 14 is driven at relatively high speed in any suitable manner. As illustrated, the shaft terminates in a coupling 40 which can be connected to a motor shaft or any other suitable driving device. A supporting bracket 44 is provided for supporting the driving motor, variable speed mechanism, or other drive mechanism. This bracket is mounted on an annular flange 45 extending about the casting 11. The flange is provided with a series of holes 46, as illustrated, so that the supporting bracket 44 may be positioned at any desired point to accommodate any given installation.

The material to be extracted is fed into the hopper 22, onto the star wheels 23. The blades 23 chop and reduce the material to small pieces. These pieces are thrown by centrifugal force against the teeth 25 of the shredding ring 24 where they are ground and chopped by the blades. This shredded and chopped material then moves downward and is thrown, pressed and rubbed against the cylindrical screen 26, where the first juice extraction is made. The fluid exudes through the screen 26 into the fluid chambers in the screen ring 27 and flows through the openings 29.

The material is gradually worked by gravity and by the incline of the rotating blades downwardly along the screen 26, to the top of the cap 31. The blades 39 on the cap press the material outwardly and downwardly against the second series of shredding teeth 30 where a still finer shredding or grinding operation is accomplished before the material is picked up by the blades 33 between the cone 32 and the conical screen 34.

The centrifugal force at this point presses the final shredded material against the screen 34 and extracts the remaining fluid therefrom. The fluid flows into the passages on the inner surface of the bell 35 and from thence through the passages 37 to the channel 19. The fluid flowing from the openings 29 associated with the upper screen falls onto the rotating bell 35 and is thrown against the inner conical wall 21 from where it flows to the collecting channel 19.

The solid material of pulp works downwardly along the screen due to the incline thereof and the centrifugal action and is thrown through the hollow center of the base casting 10. The lower rim of the bell 35 is grooved so as to provide two annular points 42. The upper one of which throws the fluid outwardly and the lower one of which throws the pulp outwardly on each side of the partition 43 which separates the juice channel 19 from the hollow interior of the base casting 10.

By adjustment of the pressure screw 18, the space between the ends of the ribs 39 and the secondary teeth 30 can be regulated so as to produce any desired degree of fineness in the final shredding.

A separating plate 41 is illustrated between the lower star wheel 23 and the cap 31. This plate

acts as a retarder to prevent a too rapid movement of the material through the machine. On some materials, this plate would be needed and on others an additional plate could be placed between two star wheels to still further retard the material.

If an additional extracting action and shredding is desired, a second cylinder 12 could be positioned above the first so as to give still additional shredding and squeezing action to the material.

It is desired to call attention to the fact that the material is first subjected to a grinding and squeezing against a stationary screen and thence to a pure centrifugal extraction against a rotating screen.

In some installations, the lower rotating assembly of the cone 32, the screen 34, and the bell 35 may not be needed as the entire extraction may be accomplished through the screen 26. In other installations the stationary screen 26 could be eliminated and the entire extraction done through the screen 34. The sectional construction admits of many changes and variations. If desired, the fluid flowing from the upper screen through the openings 29 may be collected separately from the fluid extracted by the lower screen 34.

The upper extremities of the ribs or blades 33 are curved sharply forward to pick up the material discharging from the teeth 30 and force it downwardly into the conical screen 34.

For some materials, the shredding portion of the machine 24 and 30 would not be required, and could be eliminated. The latter would be true for materials not requiring shredding or maceration, such as fine granular material requiring dewatering, for instance sugar, ores, etc., or for sewerage.

While a specific form of the improvement has been described and illustrated herein, it is desired to be understood that the same may be varied, within the scope of the appended claims, without departing from the spirit of the invention.

I use the word "juice" or its derivatives in the appended claims in a generic sense to include water, oil and other liquids, as well as those commonly called juices.

Having thus described the invention, what is claimed and desired secured by Letters Patent is:

1. In a juice extractor, a vertical shaft; a conical member secured to said shaft; blades extending outwardly from said conical member to form a conical supporting surface; a conical screen supported by said blades; a conical bell surrounding said screen in spaced relation therefrom, said bell rotating with said screen; means for introducing material between said conical member and said screen; and means for discharging juice from between said bell and said screen.

2. In a juice extractor, a vertical shaft; a conical member secured to said shaft; blades extending outwardly from said conical member to form a conical supporting surface; a conical screen supported by said blades; a conical bell surrounding said screen in spaced relation therefrom, said bell rotating with said screen; a conical cap over said conical member to direct material between said conical member and said screen; and means for discharging juice through said bell, said conical member, screen, cap, and bell rotating as a unit.

3. In a juice extractor of the class described, the combination of a vertical shaft; an inverted cup-like member axially secured on said shaft;

ribs projecting outwardly from said cup-like member; an annular screen surrounding said member and spaced therefrom by said ribs; an annular bell surrounding said screen; and inwardly extending members on said bell to hold the latter spaced from said screen, all of said elements rotating as a unit with said shaft.

4. In a juice extractor of the class described, the combination of a vertical shaft; an inverted cup-like member axially secured on said shaft; ribs projecting outwardly from said cup-like member; an annular screen surrounding said

member and spaced therefrom by said ribs; an annular bell surrounding said screen; inwardly extending members on said bell to hold the latter spaced from said screen; all of said elements rotating as a unit with said shaft, there being passages for feeding pulp between said cup-like member and said screen adjacent the top thereof, and there being passages through said bell adjacent the bottom thereof for the exit of juice therefrom.

HENRY G. SCHWARZ.
